UNITED STATES PATENT OFFICE.

ELLERY I. GARFIELD, OF LEXINGTON, MASSACHUSETTS.

DESIGN FOR A SPOON, &c.

SPECIFICATION forming part of Design No. 20,846, dated June 23, 1891.

Application filed April 9, 1891. Serial No. 388,294. Term of patent 7 years.

To all whom it may concern:

Be it known that I, ELLERY I. GARFIELD, a citizen of the United States, residing at Lexington, in the county of Middlesex and State 5 of Massachusetts, have invented and produced a new and original Design for the Ornamentation of Spoons, Knives, Forks, or other Similar Articles of Table-Ware, of which the following is a specification, reference being had 10 to the accompanying drawing, forming part thereof.

The leading-feature of my design consists in the figure of a minute-man, which is produced in any suitable manner upon the spoon- 15 handle, shown in the accompanying drawing as made with an oval top and tapering down to the bowl. This figure is shown in the accompanying drawing as placed within the oval top of the spoon.

20 Referring to the accompanying drawing, in

which I have illustrated my design, A represents a spoon, and B a figure of a minute-man placed near the end of the handle, while upon the handle of the spoon I have shown the word "Lexington," and the figures "1775," which 25 constitute no part of my invention, and may obviously be omitted without departing from my design.

What I claim as new, and desire to secure by Letters Patent, is—

30 The design for spoons, &c., having the shape and ornamentation substantially as herein shown and described.

In testimony whereof I have hereto set my hand this 7th day of April, 1891.

ELLERY I. GARFIELD.
